SPARK PLUG

Gilbert H. Palmer, Ardmore, Okla.

Application May 11, 1945, Serial No. 593,199

1 Claim. (Cl. 123—169)

1

The present invention relates to new and useful improvements in spark plugs of a type designed for use in internal combustion engines.

An important object of the present invention is to provide a spark plug of this type embodying means for intensifying the current through the provision of gaps in the conductor leading to the electrodes at the inner end of the plug and across which a firing current must jump.

A further object of the invention is to provide upper and lower spark gaps in the spark plug and enclosing the upper gap in a transparent body by means of which the spark between the upper gaps may be observed to determine whether the plug is properly functioning without necessitating a removal of the plug from the engine.

A further object is to provide a device of this character of simple and practical construction, which is efficient and reliable in operation, relatively inexpensive to manufacture and otherwise well adapted for the purposes for which the same is intended.

Other objects and advantages reside in the details of construction and operation as more fully hereinafter described and claimed, reference being had to the accompanying drawing forming part hereof, wherein like numerals refer to like parts throughout, and in which:

Figure 1 is a longitudinal sectional view, and

Figures 2 and 3 are transverse sectional views taken respectively on lines 2—2 and 3—3 of Figure 1.

Referring now to the drawing in detail, wherein for the purpose of illustration I have disclosed a preferred embodiment of the invention, the numeral 5 designates the body of the spark plug constructed of suitable insulation material having a reduced extension 6 at its lower end formed with external threads 7 for threadedly connecting the spark plug in the usual spark plug opening of the cylinder of an internal combustion engine in a manner well known in the art.

A pair of electrodes 8 have one end embedded in the extension 6 and extend vertically therein at diametrically opposite sides of the extension and with a portion of the sides of the electrodes exposed at the sides of the extension between the threads 7, as indicated more clearly in Figure 3 of the drawing, whereby to contact the engine block to provide a ground for the plug.

The lower ends of the electrodes 8 extend below the extension 6 and project inwardly toward each other, as indicated at 9, and slightly spaced from each other and also spaced below the lower end of an electrode 10 extending axially through the

2

body 5 and the extension 6 to form a spark gap at the lower end of the plug.

The upper portion of the electrode 10 is formed with lugs 11 embedded in the body 5 to anchor the electrode in the body.

The upper end of the electrode 10 extends upwardly above the body 5 and is formed with an enlarged head 12.

The head 12 is positioned in a chamber 13 formed in the lower portion of an elongated cap 14 preferably of frusto-conical shape and constructed of glass, or other suitable transparent insulation material.

The bottom of the cap 14 is fused, welded, or otherwise suitably secured to the top of the body 5, as indicated at 15.

The cap 14 is formed with a bore 16 in which a conductor 17 is positioned having a head 18 at its lower end positioned in the chamber 13 and spaced above the head 12 of the electrode 10.

The upper end of the conductor 17 is threaded and the conductor is maintained in spaced relation from the sides of the bore 16 by means of a spacing sleeve or bushing 19 in the upper end of the bore.

A nut 20 is threaded on the upper end of the conductor 17 for securing an ignition wire 21 thereto above a lock nut 22 threaded on the conductor for securing the latter in adjusted position in the cap 14 to regulate the gap between the heads 12 and 18.

In the operation of the device, the current passing through the spark plug must jump the gap between the heads 12 and 18 whereby to intensify the current before reaching the gap between the electrodes 9 and 10 at the lower end of the plug.

The gap between the heads 12 and 18 may be adjusted by means of the nuts 20 and 22 and the spark, jumping between the heads 12 and 18, may be observed through the transparent cap 14 without necessitating a removal of the spark plug from the engine to thus determine whether the plug is properly firing.

If desired the body 5 and the threaded extension 6 may also be formed of transparent material to permit inspection into the cylinder to observe whether the lower spark gap is properly functioning.

It is believed the details of construction, manner of operation and advantages of the invention will be readily understood from the foregoing without further detailed explanation.

While I have herein shown and described a preferred embodiment of my invention, it will be understood that various changes may be made in

the construction and arrangement of the parts and various modifications resorted to without departing from the spirit of the invention or the scope of the appended claim.

Having thus described the invention, what I claim is:

A spark plug comprising a main body of dielectric material having a central electrode fixed therein and projecting a substantial distance above the top and below the bottom thereof, a pair of diametrically opposed ground electrodes affixed in the sides of the lower portion of the body and terminating in spaced relation to the lower end of the central electrode, a riser of transparent material of upwardly tapering form secured at its lower portion to the top of the main body, said riser having an opening in the lower portion thereof for receiving the upper end of the central electrode, said riser being formed with an opening extending upwardly from the first mentioned opening and through the top of the riser, a spacing sleeve in the upper portion of the riser, a supplemental central electrode extending down-

wardly through the sleeve and terminating within the first mentioned opening in spaced relation to the upper end of the central electrode, and means for adjusting and locking the supplemental electrode longitudinally in the riser and with respect to the central electrode.
